CLAIM

(52) **U.S. Cl.**

The ornamental design for an operational panel for machine tool, as shown and described.

USPC **D15/28**

DESCRIPTION

(58) **Field of Classification Search**

FIG. 1 is a front view of a first embodiment of an operational panel for machine tool;

USPC D15/28; D14/315-327, 391-399, 341,
D14/345, 440; D18/1, 2, 7, 11,
235/145 A, 145 R; 341/22, 23; 345/104,
345/156, 168, 169, 173; 361/679.08,
361/679.09, 679.11, 679.26, 679.27;
D3/269, 298, 299
CPC G06F 1/16; G06F 1/1616; G06F 1/1626;
G06F 1/1632; G06F 1/1613; G06F
1/1601; G06F 1/1618; G06F 1/162; G06F
1/1628; G06F 3/0221; G06F 3/0216;
H01R 35/02; H03M 11/00; G09B 13/04;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front view thereof showing display parts; and,

FIG. 8 is a front view thereof showing an operation state.

(Continued)

The broken lines in the drawings depict environmental subject matter only and form no part of the claimed design.

1 Claim, 8 Drawing Sheets
